[57] CLAIM

The ornamental design for a shelving support pad for brackets, as shown and described.

DESCRIPTION

FIG. 1 is a perspective view of the top and one side of a shelving support pad for brackets showing my new design;

FIG. 2 is a top view;

FIG. 3 is a front elevational view;

FIG. 4 is a side elevational view;

FIG. 5 is a bottom view.

The view of the other side is identical to the side shown in FIG. 4. The view of the rear is identical to the front shown in FIG. 3.

The phantom lines in FIG. 2 represent part of a bracket not forming part of the design herein. The phantom lines in FIG. 4 represent part of a shelf not forming part of the design herein.

FIG. 1

FIG. 2

FIG. 3

FIG. 4

FIG. 5
